UNITED STATES PATENT OFFICE.

PETER SCHNURR, OF CHICAGO, ILLINOIS.

RUG-BEATER.

1,307,025.

Specification of Letters Patent. Patented June 17, 1919.

Application filed March 22, 1918. Serial No. 224,020.

To all whom it may concern:

Be it known that I, PETER SCHNURR, a subject of the Emperor of Germany, residing at Chicago, in the county of Cook and 5 State of Illinois, have invented new and useful Improvements in Rug-Beaters, of which the following is a specification.

The invention is designed for the purpose of providing a unique, efficient and durable 10 machine for the purpose of beating rugs, carpets and similar articles. The invention consists essentially of a main platform on top of which there is journaled in suitable bearings a main shaft to which motion is 15 intended to be imparted by a suitable prime mover. This shaft connects with and oscillates a pair of paddles, the oscillations of the two being in opposition. The platform is further provided with a vertically 20 adjustable frame on which the rug or carpet to be beaten is hung, this frame holding the carpet or rug in such a position that it may be played upon by the paddles.

The drawings illustrate and the specification 25 describes what at present is thought to be the preferred embodiment of the invention. The actual reduction to practice, may however, suggest certain desirable changes or alterations, and the right is 30 claimed to make any which are comprehended in spirit by the annexed claims.

A uniform system of designating the various parts obtains in all of the figures of the drawings, wherein:

35 Figure 1 is a top plan view of the improved beater,

Fig. 2 is a side elevational view,

Fig. 3 is a section on the line 3—3 of Fig. 2,

40 Fig. 4 is a section on the line 4—4 of Fig. 2.

Fig. 5 is a section on the line 5—5 of Fig. 2.

In the drawings there is shown, a platform 1 which may be either the flooring of 45 a room or a separate platform to be mounted upon a table or a suitable stand. Adjacent to one end, the platform carries the two hangers 2 in suitable bearings at the top 50 of which the main shaft 3 is journaled. This main shaft 3 carries a driving pulley 4 over which the driving belt 5 is trained, the latter passing through an opening 6 formed in the platform and being trained over the 55 pulley 7 carried by the prime mover for

the device which in this instance is an electric motor 8.

Disposed longitudinally on the platform 1, there are two guides spaced uniformly throughout their length, each guide comprising preferably an angle iron 9, one flange of which is bolted or otherwise suitably held to the platform. The two angle irons comprising each guide are so arranged that a space is provided between 60 their upstanding flanges, and in these spaces thus provided, the slide bars 10 are slidingly mounted.

Near one end of the platform 1, there are mounted two pairs of upstanding supports 70 11, between the individuals of each pair of which a shaft 12 is supported, this shaft being mounted in suitable bearings and designed for oscillating movement, being machined with hub portions 13 which stand 75 directly above the slide bars 10. The rock shafts 12 operate as the means for maintaining the beating paddles 14 in an upright position, and to this end, the hub portions 13 have formed therein the transverse slots 80 15 in which the paddles 14 loosely engage. At their lower ends, the paddles 14 are bifurcated and straddle the slide bars 10, pins 16 pivotally connecting the paddles at 85 their lower ends with the slide bars.

The paddles 14 are caused to oscillate and thereby to perform their beating function by means of mechanism connecting them with the shaft 3. This mechanism comprises a bracket 17 suitably mounted on 90 the platform 1 to one side of one of the guides, and this bracket is arranged to support in a vertical position a shaft 18 mounted for rotary movement in suitable bearings formed in the bracket. At the upper end, 95 the shaft 18 is equipped with the beveled spur gear 19 and this gear meshes with the beveled pinion 20 carried on one end of the shaft 3. At the lower end the shaft 18 carries a radially disposed arm 21 performing the function of a crank.

One of the slide bars 10 near that end where it connects with its attendant paddle carries on its side the laterally projecting arm 22 which is maintained normally in 105 a right angle position on the bar by the brace members 23. This arm 22 and its brace members are attached to the bar 10 where it requires the cutting away of the upstanding flange of the angle iron 9 to 110

provide the clearance space 24, so that the bar 10 may be readily reciprocated. A link 25 connects the outer end of the arm 22 with the outer end of the crank 21 and, since 5 the latter is caused to rotate by the rotation of the shaft 18, a reciprocating movement is imparted to the bar 10 in consequence.

A steadyng slide bearing 26 is provided for the arm 21 adjacent the point where the 10 braces 23 connect with the latter.

Since it is intended that the two paddles 14 shall oscillate in opposite directions, an oscillating bar 27 is pivotally supported at its longitudinal center on a pin or stud 15 28 mounted in the platform 1 at an intermediate position between the two guides comprising the angle irons 9. This bar 27 extends transversely to either side of the two guide members, the upstanding flanges 20 of their associated angle irons being cut away to provide clearance spaces 29 to permit the bar 27 to oscillate freely. The bar 27 is engaged by both the bars 10 and to permit such engagement, the latter are provided with the slots 30 through which the 25 ends of the bar 27 loosely pass. These ends of the bar 27 have the slots 31 formed in them and the legs thus provided by the formation of these slots straddle the pins 32, one of which is inserted through each bar 10 so that it crosses the slot 30 formed in the latter. It will thus be observed that the construction just described provides for reciprocating movement of the two bars 30, but since only one connects directly with the arm 21 and in turn transmits its motion through the oscillating bar 27 to the other bar, the two bars are reciprocated in opposite directions and the oscillating 35 movements of their attendant paddles are thus oppositely disposed.

To provide means for supporting rugs, carpets and the like which are operated upon by the paddles 14, there is provided 45 an open substantially right triangular shaped frame 33, the lower bar of which lies parallel to the platform 1. This frame 33 is mounted for vertical adjustment and to that end there are provided the up- 50 standing supports 34 and 35, the one on one side of the platform 1, the other on the other side of said platform. The support 34 and also the support 35 are provided with the longitudinal slots 36, the 55 slot in the former receiving one end of the frame 33, and the slot in the latter receiving for sliding engagement therein the guides 37 with which the frame 33 is formed.

The frame 33 is designed for vertical movement in the upstanding supports 34 and 35 and to assist in making this movement free, there are provided the rollers 38 rotatably mounted on either side of the frame, at the top and bottom of the latter and rolling 10 on the inner faces of the upstanding sup-

ports. The uppermost of the guides 37 is internally threaded to permit its effecting threading engagement with the screw 39. The others of these guides may or may not be threaded, as desired. The screw 39 at 70 its lower end carries a beveled gear 40 and this beveled gear meshes with a beveled gear 41 capable of being turned by a crank 42, a thrust bearing for the screw and a suitable support for the gear 41 and its crank 42 being provided in the form of a bracket 43 mounted on the support 35.

It is obvious that the turning of the crank 42 will operate to raise or lower the frame 33 and thus there is provided a means for 80 the vertical adjustment of the frame. The frame is designed to carry the rug or carpet which is to be subjected to the beating operation and such a rug or carpet is hung over the lower bar of the frame where it 85 will hang in a position to be operated upon by the paddles 14 when the latter are oscillated. In Fig. 3 there is shown a rug 44 in position to be subjected to a beating operation.

In the foregoing description and the accompanying drawings, it is thought that the construction and operation of the invention have been clearly enough set forth to render further description unnecessary.

What is claimed is:—

1. A device of the character set forth comprising a rug supporting frame, a pair of guides, slide bars mounted in the guides, oscillating paddles, a main shaft, connections between the main shaft and one slide bar, whereby the latter is reciprocated, connections between the said slide bar and the other slide bar whereby that is reciprocated but oppositely as respects the first, and connections between the slide bars and the paddles.

2. A device of the character set forth comprising a rug supporting frame, a pair of guides, slide bars mounted in the guides, rock shafts provided with longitudinal slots, supporting bearings for the shafts, paddles passing loosely through the said slots, a main shaft, connections between the main shaft and one slide bar whereby the latter is reciprocated, connections between the said slide bar and the other slide bar whereby that is reciprocated but oppositely as respects the first, and connections between the slide bars and the paddles.

3. A device of the kind set forth comprising a rug supporting frame, a pair of guides, slide bars mounted in the guides, oscillating paddles, a main shaft, connections between the main shaft and one slide bar whereby the latter is reciprocated, an oscillating bar pivotally mounted at its longitudinal center and formed with end slots, each of the slide bars having a pin playing in one of the said slots, and con-

nections between the slide bars and the paddles.

4. A device of the character set forth comprising a platform, a rug supporting 5 frame mounted on the platform, a pair of guides also mounted on the platform, slide bars mounted in the guides, rock shafts provided with longitudinal slots, supporting 10 bearings for the rock shafts, paddles passing loosely through the said slots, a main shaft, connections between the main shaft and one

slide bar whereby the latter is reciprocated, an oscillating bar pivotally mounted at its longitudinal center and carried upon the platform, the said bar being formed with a 15 longitudinal slot at each end, the slide bars having pins playing in said slots, and connections between the slide bars and the paddles.

In testimony whereof I affix my signature. 20

PETER SCHNURR.
